US00D648138S

(12) **United States Design Patent**
Lee

(10) **Patent No.:** US D648,138 S
(45) **Date of Patent:** ** Nov. 8, 2011

(54) **SHEET WITH PATTEN**

(75) Inventor: **Ji-Yoon Lee**, Seoul (KR)

(73) Assignee: **LG Hausys, Ltd.**, Seoul (KR)

(**) Term: **14 Years**

(21) Appl. No.: **29/376,656**

(22) Filed: **Oct. 8, 2010**

(30) **Foreign Application Priority Data**

Jul. 9, 2010 (KR) 30-2010-0030177

(51) **LOC (9) Cl.** **05-06**

(52) **U.S. Cl.** **D5/60**

(58) **Field of Classification Search** ..... D5/4, 7, D5/47, 53, 56–59, 60–63, 99; D6/582, 585, D6/586, 612, 622; D11/165; D19/5; D24/124–126; 4/581; 5/490, 495; 15/208, 215; 112/401, 112/402; 139/383 B, 383 R, 420 R; 162/134; 428/57, 66.5, 187, 221, 542.2, 542.6; 604/385.01

(57) **CLAIM**

The ornamental design for a sheet with patten, as shown and described.

DESCRIPTION

The sole FIGURE is a top plan view of a sheet with patten showing a new ornamental design.

The dotted lines forming a rectangle are solely to depict outer boundaries of the claimed design and form no part of the claimed design. The pattern within the boundaries forms the claimed design.

1 Claim, 1 Drawing Sheet
